WORM DRIVE TOY LOCOMOTIVE

Marshall H. Frisbie, Hamden, Conn., assignor to
 The A. C. Gilbert Company, New Haven, Conn.,
 a corporation of Maryland

Application November 8, 1940, Serial No. 364,818

18 Claims. (Cl. 105—49)

This invention relates to electrically powered toy locomotives particularly of the type deriving current supply from rails of a toy track as by a collector shoe or the like.

An heretofore constructed the typical electric locomotive for pulling toy trains has been of relatively intricate construction involving a complicated piece-by-piece assemblage of parts. In the case of toy locomotives having multiple driving or traction wheels there has customarily been employed a system or train of heavy and costly spur gears for transmitting driving power individually to each traction wheel.

A general object of the present improvements is so to construct an electrically driven toy locomotive that the individual parts thereof may be grouped and handled together as unitary sub-assemblies in order that each such sub-assemblies may be produced complete and independently of any associated sub-assembly, and so that like unitary sub-assemblies can be used interchangeably in toy locomotives of different external modeling, and with different other unitary sub-assemblies.

A related object is to use different combinations of a given group of various sub-assemblies for producing toy locomotives differing in overall length, appearance of power, etc.

A further important object is to employ toothed gearing preferably consisting of a simple worm and worm wheel to transmit the power of the electric driving motor of the locomotive to a single pair of its wheels which hereinafter are referred to as the drive wheels, and to employ instead of repetitious spur gearing simple linkage connections for relaying this power to as many other pairs of traction wheels as it may be desired to incorporate in the locomotive.

A further object of the invention is to provide simplified and dependable automatic electric switching devices for determining whether the locomotive shall run backward or forward, to provide improvements in the construction of its current collecting devices, and in its means for weighting, and to improve the construction and arrangement of auxiliary wheels or trucks additional to the drive wheel and traction wheels.

A still further object of the improvements is to make the major parts of the improved locomotive of relatively nestable nature and in other ways to compact the organization of such parts and reduce the number of machining and assembling operations required. This also permits the toy locomotive to be fashioned as a more faithful reproduction of the actual locomo-

tives which haul modernized nationally famous long run trains.

Associated objects are to make locomotives of the above types less likely to get out of order during use as a plaything or hobby, and to make them sufficiently lower in cost to thereby become available to a far larger market than has heretofore been able to possess completely equipped and realistic types of toy and model railroad locomotives.

With the foregoing and other objects in view, the present improvements will be understood as capable of embodiment in a wide variety of structural forms from which I have chosen to illustrate herein a preferred example which will be understood in fuller detail from the following description having reference to the accompanying drawings, wherein:

Fig. 1 is an elevation of a toy locomotive embodying the present improvements and showing a section of the track on which it runs.

Fig. 2 is a bottom plan view looking upward at Fig. 1 with track rails omitted.

Fig. 3 is a view similar to Fig. 1 showing the outer shell of the locomotive and certain interior parts in section on the plane 3—3 in Fig. 2 looking in the direction of the arrows.

Fig. 4 is a fragmentary view of the motor reversing switch showing the opposite side from that appearing in Fig. 3, with the switch actuating pawl in dropped position.

Fig. 5 is a fragmentary plan view taken in section on the plane 5—5 in Fig. 3.

Fig. 6 is a view similar to Fig. 5 showing the switch actuating pawl positioned as in Fig. 4.

Fig. 7 is a fragmentary view taken in section on the plane 7—7 in Fig. 3 showing the switch actuating pawl locked in raised position.

Fig. 8 is a view corresponding to Fig. 7 showing the switch actuating pawl unlocked in dropped position.

Fig. 9 is an enlarged fragmentary view taken in section on the plane 9—9 in Fig. 5 looking in the direction of the arrows.

Fig. 10 is an enlarged fragmentary view taken in section on the plane 10—10 in Fig. 6 looking in the direction of the arrows.

Fig. 11 is a bottom perspective view of the locomotive shell with its interior empty.

Fig. 12 is a perspective view of a member of the hollow chassis structure or carriage frame emptied and detached from the outer shell of Fig. 11.

Fig. 13 is a perspective view of the weighting

block removed from the hollow interior of the carriage frame of Fig. 12.

Fig. 14 is an exploded view of parts of the electric drive motor and the rear end of the carriage frame with which they are assembled, sections of certain parts being broken away better to show their constructions.

Fig. 15 is a view taken in section through the drive motor on the plane 15-15 in Fig. 3 looking in the direction of the arrows.

Fig. 16 is an enlarged view taken in section through one of the drive wheels on the plane 16-16 in Fig. 1.

Fig. 17 is a view on a correspondingly enlarged scale taken in section through a link connected traction wheel on the plane 17-17 in Fig. 1, looking in the direction of the arrows.

Fig. 18 is a fragmentary view taken in section through the hollow carriage frame on the plane 18-18 in Fig. 3 looking downward on the current collector unit.

Fig. 19 is a perspective view of the headlight lamp and its holding bracket detached from the shell of the locomotive.

Fig. 20 is a diagram of the wiring connections.

Fig. 21 is an elevation drawn on a smaller scale than Fig. 1 showing a toy locomotive incorporating the present improvements and provided with an additional pair of traction wheels.

Fig. 22 is a view of the end of the motor looking in the direction of arrow 22 in Fig. 3.

Fig. 23 is a sectional view taken on the plane 23-23 in Fig. 3 looking in the direction of the arrows and drawn on a slightly reduced scale.

The carriage frame 10 for the driving mechanism comprises part of the chassis structure of the locomotive and according to the present improvements carries nearly all of the major working parts of the locomotive and such parts are grouped in compact subassembled units, each of which units may be applied to or removed from frame 10 alone. These subassembled units include the electric power motor of Fig. 14 which as a composite unit is designated by 11, the pair of driving wheels 12 and 13, one or more additional pairs of traction wheels as 14, 15 with their connecting pitmans or linkages, the double-shoe current collector of Fig. 18 designated as a whole by 16, the electromagnetically operated reversing switch of Figs. 4 to 10, inclusive, indicated as a whole by 17, and the ballast block 18. Each of the above named subassembled units is described in greater detail hereinafter.

Carriage frame 10 is representative of various possible forms of chassis frames and as herein shown is conveniently formed as an inverted, box-like hollow die casting as shown in Fig. 12 and is provided with external mounting lugs 22 located at the front end and 23 located near its rear end to aid in securing thereto the outer shell 19 of the locomotive. Shell 19 also may comprise a thin walled hollow die casting whose contours provide interior bosses 24 whose ends abut against lugs 22, respectively. In the die casting 19 there is further formed the interior bosses 25 each of which has fixed against its bottom end a shelf plate 26 as by peaning over a stud 27 of the die cast metal which stud projects through a hole in plate 26. A notch 28 in each mounting lug 23 is engaged and occupied by one of the shelf plates 26 when frame 10 is inserted into the hollow interior of the locomotive shell 19 and the frame can then be thrust rearward lengthwise so that screws 29 can be inserted through notches 30 in the mounting lugs 22 to engage threaded holes 31 in the bosses 25.

24. In this manner the locomotive shell 19 and the frame 10, together with all of the equipment carried respectively by each of these two major die cast parts of the locomotive, may quickly be fastened together and taken apart in manufacture or servicing by the use of the simple two screws 29. Rugged assemblage and accurate relative positioning of the parts result.

The die cast metal of frame 10 may be shaped 10 at its rear end to receive and support an electric motor 11 by which the locomotive is powered. This same rear end of the frame provides suitable bearing for a drive shaft serving to transmit power from motor 11 to the drive wheels 12 and 13. 15 These features of the rear end of the die cast frame appear most plainly in Figs. 3, 12 and 14. The end wall 35 of frame 10 is seen to be thickened and to contain an inclined elongated hole in which is lodged the bearing bushing 36 having a thrust head 37. Bushing 36 receives and affords bearing for motor shaft 38 on which is cut a preferably double worm thread 39. On a common axis disposed crosswise of frame 10, the side walls of this frame are provided with a pair of bearing holes 40 which are elongated by extending through bosses 41 cast on the inside surface of the frame wall. Additional pairs of bearing holes alternatively usable are shown at 60, 61 and 62. In bearing holes 40 axle shaft 45 is journaled. On the outer ends of shaft 45 there are fixedly assembled with a press fit the drive wheels 12 and 13. Fixed on shaft 45 centrally of its length is the worm gear 46 with which worm threads 39 of motor shaft 38 are in mesh.

The parts of motor 11 which are supported on and overhang the rear end wall 35 of the frame include a stator 41 carrying the field winding 48 and having at least two diametrically opposite holes, as 49, fitting corresponding dowel projections 50 standing out from the rear face of frame wall 35. There are at least two other diametrically opposite holes, as 51, through which may pass holding screws 52. The motor shaft 38 carries the usual armature 53 and commutator 54. The extremity of shaft 38 flanking commutator 54 is provided with a bearing 44 in the end cap 55 which latter may be considered a part of the frame structure of the motor and made of insulative material having at least two dowel projections 56 receivable in the before mentioned holes 49 of the motor stator. The end cap 55 likewise carries at least two diametrically opposite holes 57 through which holding screws 52 pass. End cap 55 also carries sockets comprising holes opening through both the front and the rear of the cap each hole being lined by the cylindrically curled end 64 of a circuit terminal strip 65 carrying the lateral binding post lug 66 to which a current lead 67 for the motor is attached as shown in Figs. 3, 14, 15 and 22. Curled strip ends 64 provide 60 guide bearings in which the brushes 58 are free to slide lengthwise through both ends of these guide bearings and from which the brushes are free to be removed rearwardly endwise. A wire spring 59 is loosely coiled about each lug 66 and an easily deflectable end of this spring bears forwardly on the free rear end of the brush to resiliently press the brush against commutator 54.

The present feature of advantage in the construction of motor 11 as described is its ready accessibility permitting convenient removal of its stator parts alone, as well as independent removability of its armature and worm shaft. The latter can at all times be unscrewed or pulled out of mesh with worm gear 46 and removed from its bearing as shown in Fig. 14. The two holding

screws 52 are the only parts which must be loosened or removed in order to take the motor entirely, or in part, away from the mechanism frame 10. These screws enter threaded holes 32 in frame wall 35.

The side walls of frame 10 are provided with pairs of coaxially aligned bearing holes additional to holes 40 which additional holes are respectively designated in pairs as 60, 61 and 62. Where only one pair of traction wheels 14 and 15 are employed additional to the drive wheels 12 and 13, the axle shaft 63 for such pair of traction wheels carries the latter fixedly pressed upon its opposite ends and has bearing in the frame holes 61. But as illustrated in Fig. 21, two or more pairs of traction wheels 68 and 69 may be employed in place of the single pair 14, 15. Corresponding axle shafts 72 and 73 may be assembled respectively therewith and may respectively be journaled in the before mentioned bearing holes 60 and 62.

The drive wheel and all traction wheels on opposite sides of the locomotive are linked together by coupling rods 70 or 70' respectively in Fig. 1, or by coupling rods 71 or 71' respectively in Fig. 21, it being understood from the broken line showing of rods 70 in Fig. 1, for instance, that each such coupling rod is pivotally connected to its drive and traction wheels on one side of the locomotive at a point angularly displaced ninety degrees in the plane of wheel rotation from the point at which the coupling rod is pivotally connected to its drive and traction wheels on the opposite side of the locomotive. Thus rod 70 is pivotally connected to wheels 13 and 15 at 75 and 76 respectively while rod 70' is pivotally connected to wheels 12 and 14 at 77 and 78 respectively in Fig. 1. In corresponding arrangement in Fig. 21 coupling rod 71 is pivotally connected to wheels 13, 68, 69 at 79, 80 and 81, respectively, while rod 71' is pivotally connected to wheels 14, 68, 69 at 82, 83, 84, respectively.

Excess linkages representative of valve gear linkage are provided by the short depending lever 88 which is suspended freely from the pivot 89 fixed on the locomotive shell 19 and by means of a floating link 90 is connected to and oscillated back and forth by a crank arm 91 fixed on and revolving with the traction wheel. Fig. 17 shows in enlarged detail how arm 91 is made fast to the crank boss 86 on traction wheel 15 by the close fit of its square aperture 85 on the squared terminus 87 of this crank boss where it is fixedly retained by screw 92 while Figs. 1, 2 and 11 show the pivotal connection of link 90 to crank arm 91 at 86 and the pivotal connection of link 90 to depending lever 88 at 93. A further idling member 94 represents a pitman and pivotally engages a round section of the same eccentric crank boss 95 on traction wheel 15 to which crank arm 91 is fast. The opposite reciprocating free end of pitman member 94 is concealed within the hollow of an outward embossed formation 96 on the locomotive shell 19 which provides a pocket and represents the steam cylinder of a real locomotive. Fig. 11 best shows elongated apertures 99 provided in the fins fixed on shell 19 within the cylinder formations 96 to receive and guide the free end of member 94 while the latter performs lengthwise, reciprocative movements as traction wheel 15 rotates. While the parts just described actually transmit no power for driving my improved locomotive they realistically imitate, in their movements which accompany travel of the locomotive, the reciprocating pitman and oscillating valve gear linkage which conspicuously operates at the sides of a real locomotive. Duplicates of

parts 88 to 96, inclusive, respectively indicated by the same numerals primed, will be understood to be present on the far side of the locomotive in Figs. 1 and 21 and appear similarly numbered in Fig. 2. In Fig. 21, members corresponding to pitman 94 and to valve gear link 90 may connect to the traction wheels 68 and this particular pair of traction wheels need not have guard flanges in their engagement with the track rails if drive wheels 12 and 13 and traction wheels 69 all have the usual guard flanges. In Fig. 21 also a further pitman-like flat rod 97 reciprocates lengthwise to represent an additional valve gear part. Rod 97 is pivoted at 98 to 98' and is guided in elongated aperture 99.

Fig. 13 shows a ballast weighting block 18, preferably solid, which may be cast of lead or other heavy material in a size and shape to fit within and more or less completely fill the hollow interior of frame casting 10 between its front wall 100 and the partition wall 101. Both of these walls are thickened to contain the threaded holes 102 which receive screws 103 by means of which the current collector subassembly unit 16 is held in place as shown in Fig. 3. The weighting block 18 is provided with four legs 104 whose bottom ends rest upon a plate 105 of insulative material which serves as the mounting base for the current collector unit 16. The weighting block is further provided with suitable vertical side grooves, as 106, and end grooves, as 107, which are engaged respectively by vertically disposed pads cast on the interior surface of mechanism frame 10, and engaged by the thickened section of walls 100, 101. Thus the weighting block, while readily removable from the interior of the carriage frame, is fixedly placed therein by its manner of assemblage and requires no removable holding means additional to the insulative plate 105. This weighting block is further provided with three crosswise extending grooves 109, 110, and 111 in its bottom surface which provide clearance for axle shafts 72, 63 and 73 respectively. A further vertical groove 112 provides passageway for an insulated wire 113 which conducts current from the collector unit 16 to the electrical parts above the frame 10. It will be understood that the internal pads, boxes and partition walls which have been mentioned as occupying the hollow of mechanism frame 10 may extend way to the top wall 114 thereof if the casting is made by a process which requires ability to withdraw a molding core. Walls 35, 100, 101 or 114 may be termed transverse walls of the box-like frame 10.

Referring specifically to the current collector subassembly unit best shown in Figs. 3 and 18, contact shoes for wiping against the "third" or power rail 118 are provided by two C-shaped members 119 whose bowed ends pass through apertures 120 in the base plate 105 and whose pivotally anchored ends 121 are turned down and loosely engage with anchorage holes in said plate 105. Thus the rail contacting surfaces of shoes 119 are free to swing up and down in conformity with unevenness of the rail top, being lightly urged downward thereagainst by opposite ends of the leaf spring 123 whose central section is secured to base plate 105 in any suitable manner as by the eyelet or rivet 124 to which is soldered the lead wire 113. It will be noted that one of the screws 103 used to hold the base plate 105 against the bottom of the mechanism frame 10 also retains a drip pan 125 positioned under worm wheel 46 to catch any drippings of oil.

With specific reference to the reversing switch subassembly unit 17 as shown in Figs. 3 to 10 in-

clude, the working parts of this switch are supported on a skeleton stand 128 which is fastened on the top of carriage frame 10 by screws 129. Stand 128 supports the solenoid 130 of an electromagnet whose plunger 131 moves vertically and carries the double ended pawl pin 132 adapted to engage with and actuate a ratchet wheel 133 step-by-step respectively corresponding to each complete excursion of pawl 132 up and down. Ratchet wheel 133 is in fixed rotative relation to a current switching drum 134 whose surface is composed partly of insulative material and partly of conductive material and which rotates in wiping engagement with two pairs of brush contacts 135 which as indicated in Fig. 20 are so connected in circuit that upon suitable occasion the direction of running of motor 11 is reversed. Brush contacts 135 are mounted on insulative panels 136 which in turn are supported by frame 128. A manual lockout lever 137 is pivoted on frame 128 at 138 and swings between positions which respectively permit and prevent vertical movement of the solenoid plunger 131.

Further details of the complete locomotive include a leading truck 141 in which are journaled the axles 142 of four small wheels 143 which truck is provided with loose pivotal connection to a lug 144 cast on mechanism frame 10 by means of the shoulder screw 145 passing through the elongated slot 146. A trailing truck 149 includes the cross bar 150 weighted at 151 and in whose turned down ends there is journaled the axle shaft 152 for wheels 153. The forward end 154 of truck 149 is provided with loose pivotal connections to the rear wall of carriage frame 10 by the shoulder screw 155 while the rear end 156 of the trailing truck overlies a cross bar 157 fixed on the locomotive shell 19 from which depends the coupling pin 158 by which the locomotive is connected to and hauls the tender, or some leading car of a toy train.

A still further improved detail of construction resides in the means for headlight illumination illustrated in Figs. 3 and 19. The nose wall of the locomotive shell 19 contains a horizontal bore 161 at the forward end of which is lodged a transparent light concentrating lens 162. In line with the rear end of bore 161 there is carried the miniature electric lamp 163 whose screw base is received in the screw shell 164 mounted on and in electrical contact with a metallic spring clip 165 adapted frictionally to engage and cling to a depending fin cast integral with the locomotive shell 19. The clinging fit of clip 165 on fin 166 insures lamp 163 against accidental displacement yet enables the screw shell 164 to be readily removed with its spring clip 165 from the cavity of the locomotive without disturbing any of the neighboring parts of the locomotive mechanism so that lamp 163 may conveniently be renewed if it burns out. The circuit contact 167 of screw shell 164 is insulated from clip 165 and has soldered to it the insulated wire 168 whose place in the electrical system will be understood from the wiring diagram of Fig. 20.

The advantages of the several features of construction described in the foregoing reside partly in the increased ease and efficiency with which the improved locomotive can be assembled, then taken down in unitary sections and in like manner reassembled, and resides in part in better operating performance of the locomotive as it starts, runs and stops on its tracks by electrical power derived through the latter. In the matter of increased ease and efficiency in manufac-

turing operations and servicing methods it will be observed that when the outer shell 19 is removed from mechanism frame 10, the latter and its various carried subassemblies make up a self contained operating unit capable of automatically traveling along an electrified track and performing all of the functions of a complete toy locomotive while in a condition in which its working parts are fully exposed for testing or observation. Such parts are then accessible for removal from frame 10 in any selective sequence without of necessity disturbing other parts which may not require servicing. Thus the brushes of motor 11 are accessible to be replaced without disturbing any other part. The motor armature 53 with its worm shaft 38 may be removed without disturbing the motor stator 41 and vice versa. The current collector assembly 16 can be removed as a unit. Likewise the reversing switch assembly 17 can be removed as a unit. A space saving advantage of this improved structural organization is the nesting of hollow frame 10 within the hollow shell 19 and the nesting of the weighting block 18 within the hollow of mechanism frame 10. Here the heavy block 18 occupies as low a position as is desirable for producing a low center of gravity for the locomotive as a whole which makes for stability against overturning without interfering with the accessibility or removability of any of the working parts of the locomotive power plant including its driving wheels and traction wheels.

Fig. 11 makes clear that the imitative valve gear linkage 88, 90 and 91 may remain attached to the locomotive shell 19 when the latter is removed from frame 10 and may be parted from the traction wheels when only pivot screws 76 and 78 are removed. This frees the locomotive wheels from entanglement with the linkages referred to while not requiring the latter to be broken down into their component parts or separated from the locomotive shell 19 thus avoiding danger of their becoming lost before reassembly. Although flexible insulated electric wires connect some of the various separately removable subassembly units, it will be observed that the cavity space above mechanism frame 10 within the outer shell 19 is sufficiently large to house looped lengths of such wires which upon being straightened out give enough play to permit generous separation of various parts of the mechanism without requiring disconnection of wire terminals. Emphasis is placed on the importance of these advantages of easy removal and replacement of subassemblies by the modern desire and practice of miniature railroad hobbyists to stock component working parts of their toy rolling stock and to place them together in different combinations at different times.

In running performance of the locomotive, the reversing motor 11 impels the locomotive forward when the motor brushes 58 and field winding 48 are electrically coupled in the circuit relationship occasioned by the position of the current switching drum 134 in relation to its stationary brush contacts 135, denoted as position A in Fig. 20. If the power rail 118 and a traction rail 117 are then electrically energized from electrical supply line 115, 116 the armature 53 of motor 11 rotates the worm 39 which turns worm wheel 46 at speed reduced in unusually great ratio as for example in ratio of 18 to 1 revolutions. Heretofore the use of spur reduction gears, has necessitated an undesirably large number of intermeshed gears to attain so great

a ratio between drive wheel and motor shaft even as 8 to 1 revolutions. It is therefore clear that not only does the motor with the present improved worm drive possess more than twice the mechanical advantage or torque power for starting a heavy load from a stand still, as when a train is on a curved section of track, as well as being free from the frictional resistance of multiple gear trains, but also there is considerably less backlash, or lost play, or looseness in the drive transmission from motor shaft to locomotive wheels so that the more closely coupled elements of this worm drive transmission system produce a positiveness in the starting and stopping and standing performance of the locomotive which is uncommon in electrically powered toy locomotives. When current is shut off from the track rails, as at a remote control and voltage modulating switch 126, the solenoid 130 becomes deenergized and plunger 131 with its pawl pin 132 drops from its high position in Figs. 7 and 9 to its low position in Figs. 8 and 10 ready to engage with the next tooth on ratchet wheel 133. At the same time, motor 11 is deprived of power and the locomotive comes to rest. Upon subsequent reenergization of the track rails, solenoid 130 lifts plunger 131 whereupon pawl 132 advances ratchet wheel 133 one step together with current switching drum 134 so that the new relation of the latter to brush contacts 135 establishes a condition of circuits indicated by position "B" in the wiring diagram of Fig. 20. In this condition one terminal of the motor field winding 48 is deadened whereby the motor is prevented from running. Upon following deenergization and reenergization of the track rails, plunger 131 respectively again drops and lifts advancing current switching drum 134 another step to establish the condition of circuits represented by position C in the wiring diagram whereby each of the motor brushes becomes connected to a different end of the motor field winding than formerly. This results in the motor running in reverse direction and causes the locomotive to travel backward. Upon subsequent deenergization and reenergization of the track rails, condition D of the switch drum 134 is brought about by the repeated dropping and lifting of the solenoid plunger so that now motor 11 is again deprived of current. This described cycle of forward running, current cut off, reverse running, and repeated current cut off is thus repeated in the sequence recited as current is alternately supplied to and cut off from the track by remote control 126. It is of course understood that motor 11 is not only a reversing motor but is also a variable speed motor and will run at a variety of speeds ranging from a very low speed to nearly as high a speed as the locomotive is capable of negotiating without derailing. At the lower speeds determined by cutting down the track voltage, the worm drive of these improvements enables the locomotive, with or without its train, to be run at considerably lower minimum speeds without stalling than it has been possible to operate toy locomotives having spur gear drives. This is because of the greater mechanical advantage possessed by the worm drive motor over its load, the elimination of frictional retarding forces and the avoidance of jerk producing looseness, all of which factors have heretofore prevented toy locomotives from satisfactorily imitating the slow and leisurely speed performances of real steam locomotives

and from starting satisfactorily on sharply curved sections of track.

Certain features embodied in the aforescribed structure are deserving of particular mention. The brushes 58 of motor 11 are accessible, removable and replaceable through the rear opening to the hollow imitative engineer's cab 20 formed at the rear end of the locomotive shell 19 by merely deflecting springs 59 away from the rear free ends of the brushes and therefore require no disassemblage of other parts of the locomotive or dismounting of springs 59 from the motor for this attention or for servicing. The brush springs 59 which lightly urge the brushes 58 against the commutator 54 are lifted rearwardly and upwardly by the operator's finger to permit removal of the brushes from their guideways in the end cap 55, which cap faces up into the engineer's cab 20 for this purpose. Brilliance of the head light is increased by making the "lens" 162 in the form of an elongated body of good light conductive molded "plastic" or other light concentrating material which is lodged in the hole 161 and for best effect should project a little from the front end thereof.

Since many departures from the exact shape, construction and arrangement of parts which I have chosen to disclose herein for illustrating the principles of the improvements are possible and will be suggested to workers in the art, my invention and the appended claims are understood and intended to comprehend and cover all substitutes and equivalents for the herein specified constructions which fairly fall within their terms.

I claim:

1. In a toy locomotive, the combination of, an inverted hollow shell modeled externally in imitation of a real locomotive including an engineer's cab at the rear, an inverted box-like chassis frame composed of closure forming walls including laterally spaced side walls joined by transverse end walls and nested at least partially within said shell, driving wheels having axle shafts journaled in said side walls of the frame, and an electric motor carried on the exterior of one of said end walls nearest said cab within the hollow interior of said shell having a shaft extending through said one of said end walls to the frame interior in a direction crosswise said axle shafts connected to impel said wheels.
2. In a toy locomotive, the combination of, an inverted hollow shell modeled externally in imitation of a real locomotive including an engineer's cab at the rear, an inverted box-like chassis frame composed of closure forming walls including laterally spaced side walls joined at the top and end by transverse closure walls and nested at least partially within said shell, driving wheels having axle shafts journaled in said side walls of said frame, an electric motor housed within said shell mounted on and external to a transverse frame wall at the rear end of said box-like chassis frame, and transmission gears housed by and within said closure forming frame walls connected to be driven by said motor and connected to drive said wheels.
3. In a toy locomotive, the combination of, a hollow inverted open-bottomed outer shell simulating a locomotive body, a hollow open-bottomed box-like chassis frame underlying and nested at least partially and fixedly within said shell, driving and traction wheels having axle shafts journaled in and spanning the width of said frame at points substantially spaced below the top of the

latter, and a ballast block shaped to accord dimensionally with the interior of said box-like frame sufficiently to be confined to a fixed position by the latter in the space above said axle shafts.

4. In a toy locomotive, an electric power plant comprising a hollow chassis structure riding on drive wheels and carrying an electric motor operatively connected to drive said wheels, said motor including a field stator and an armature having a shaft, the said stator being mounted on the exterior of said chassis structure in a manner to be removable therefrom without taking said structure apart, and said armature shaft being journaled in said chassis structure in a manner to permit removal of said shaft and armature from said chassis structure independently of said stator.

5. Worm drive mechanism for a toy locomotive, embodying the combination of, a chassis frame composed of walls housing a cavity, one of said walls containing a bearing hole extending therethrough and opening both to said frame-housed cavity and to the exterior of the frame, an axle shaft rotatably journaled in said frame and spanning said cavity, drive wheels on said shaft at the sides of said frame, a worm gear fast to said shaft between said drive wheels, an electric motor including an armature and a field stator mounted on said frame, and an armature shaft journaled in said bearing hole between said armature and said worm gear and provided with worm threads in mesh with said worm gear.

6. Worm drive mechanism for a toy locomotive, embodying the combination defined in claim 5, together with a bearing cap on the opposite side of the said motor stator from said chassis frame having the said motor shaft journaled therein.

7. Worm drive mechanism for a toy locomotive, embodying the combination defined in claim 5, together with means carried by the said chassis frame wall which contains the said bearing hole for locating and fastening the said motor stator thereto in predetermined fixed relation to said bearing hole.

8. In a toy locomotive, an electric power plant comprising a hollow chassis structure riding on drive wheels and carrying an electric motor operatively connected to drive said wheels, said motor including a stator having a bearing cap and an armature having a shaft journaled in said chassis structure and in said cap, the said stator being mounted on the exterior of said chassis structure and the said bearing cap being detachably mounted on said stator in a manner to permit removal of said cap and armature shaft from said chassis structure and stator without taking apart said chassis structure.

9. In a toy locomotive, the combination of, a hollow carriage frame, a bearing opening into the hollow of said carriage frame, drive wheels supporting said frame having an axle journaled in the latter, a worm gear on said axle within the hollow of said carriage frame, a motor stator fixedly mounted on said frame, and a motor armature external to said frame including a shaft provided with worm teeth meshable with said worm gear, and having a portion of its length as large in diameter as said worm teeth journaled in said frame whereby said worm teeth may be withdrawn from the hollow of said carriage frame through said bearing.

10. In a toy locomotive, the combination of, a carriage frame, drive wheels supporting said

frame having an axle journaled in the latter, a worm gear on said axle, a motor stator fixedly mounted on said frame, a motor armature including a disc commutator and a shaft provided with 5 worm teeth meshable with said worm gear, a portion of said shaft being as large in diameter as said worm teeth and journaled in said frame, an end cap detachably mounted in fixed relation to said stator and frame and affording bearing

10 for said armature shaft, and removable brushes supported by said end cap side-by-side in positions to bear against the flat face of said disc commutator thereby to be separable from said cap in a common direction of removal.

15 11. In a toy locomotive, in combination, an outer shell modeled in imitation of an engineer's cab containing a hollow compartment having a rear opening admissive to the fingers of an operator's hand, an electric motor including an armature and an armature shaft for driving the locomotive aligned with the general direction of locomotive travel, a disc commutator on said shaft between said armature and said rear opening having a face disposed toward the latter, at least

20 two elongated free ended rod-like brushes, and guide means between said commutator face and said rear opening constraining said brushes to lengthwise sliding movement in a path aligned with said general direction of locomotive travel, 25 said guide means permitting endwise removal of said brushes therefrom so that at least the rear end portions of said brushes may be grasped by the operator's fingers for manipulating the brushes and removing or inserting the same end-

30 wise through said rear compartment opening.

12. In a toy locomotive, in combination, a body casing having an opening admissive to the fingers of an operator's hand, an electric motor including an armature and an armature shaft for driving

35 the locomotive aligned with the direction of locomotive travel, a disc commutator on said shaft having a flat face disposed toward said casing opening, at least two elongated free-ended rod-like brushes within said body casing aligned lengthwise with said casing opening, and guide

40 means constraining said brushes to a path of lengthwise movement directed through said casing opening and toward and away from the flat face of said commutator, both ends of each of 45 said brushes being free and separable from both said face and said guide means thereby to be removable and insertable through said casing opening.

13. In a toy locomotive, an electric power plant 55 comprising an elongated chassis riding lengthwise and supported by drive wheels constituting at least four points of support for said chassis, an electric motor detachably mounted on said chassis in a position offset lengthwise from said points of chassis support, and a ballast block at least as heavy as said motor carried by and in fixed relation to said chassis within an area embraced between said four points of chassis support, thereby to counterbalance the relatively offset weight 60 of said support and to insure tractive effect for each of said drive wheels.

14. In a toy locomotive, the combination of, a hollow inverted open-bottomed outer shell simulating a locomotive body, a hollow open-bottomed box-like frame underlying and nested at least partially within said shell, driving and traction wheels having axle shafts journaled in and spanning the width of said frame at points substantially spaced below the top of said frame, a ballast block occupying the hollow interior of

said frame above said axle shaft, and a current collector device including a base panel spanning and secured to the open bottom of said box-like frame beneath both said ballast block and said axle shafts cooperative with said ballast block to confine the latter within the hollow of said frame.

15. In a toy locomotive, the combination of, a hollow inverted open-bottomed outer shell simulating a locomotive body, an open-bottomed hollow box-like chassis frame under and nested at least partially within said shell, driving and traction wheels having axle shafts journaled in and spanning the width of said frame, a ballast body occupying the hollow interior of said box-like frame and separable therefrom, and a current collector including a base panel spanning the open bottom of said frame below said axle shafts and removably secured to said frame, said ballast body being constructed and arranged to stand and rest on said base panel.

16. An electrically powered toy locomotive embodying in combination, an elongated chassis frame hollow throughout its length, a ballast block partially filling the hollow of said frame in a manner to leave a cavity within one end of the frame, a plurality of pairs of wheels spaced lengthwise of said frame, an axle shaft connecting the wheels of one of said pairs and extending through said cavity, at least one other pair of said wheels flanking a portion of said chassis frame occupied by said ballast block thereby to be weighted by the latter, a gear carried by said shaft in said cavity, an electric motor carried by said chassis frame outside of said cavity and con-

nected to impel said gear thereby to drive said one of said pairs of wheels, and connecting rods constructed and arranged to constitute the sole means of transmitting movement from said one of said pairs of wheels to said other of said pairs of wheels.

17. In a toy locomotive, the combination of, an inverted hollow shell modeled externally in imitation of a real locomotive, an inverted box-like chassis frame composed of closure forming walls including laterally spaced side walls joined at the top and end by transverse closure walls and nested at least partially within said shell, driving wheels having axle shafts journaled in said walls of said frame, an electric motor carried at the end of and exterior to said frame on one of said transverse walls thereof within the hollow interior of said shell and connected to impel said wheels, together with an electromagnetically operated current switch having electrical connection with said motor and carried exterior to and atop said frame on one of said transverse walls thereof within the hollow interior of said shell.

18. In a toy locomotive, in combination, a power plant including a chassis frame having holding lugs provided with laterally disposed notches, an outer shell larger than and superimposed over said chassis frame, and shell-like elements fixed on the interior of said shell projecting laterally into said notches thereby to engage with said lugs in a manner to restrain relative up and down movement between said outer shell and said chassis frame.

MARSHALL H. FRISBIE.

CERTIFICATE OF CORRECTION.

Patent No. 2,348,616.

May 9, 1944.

MARSHALL H. FRISBIE.

It is hereby certified that error appears in the printed specification of the above numbered patent requiring correction as follows: Page 7, second column, line 28, claim 18, for "shell-like" read --shelf-like--; and that the said Letters Patent should be read with this correction therein that the same may conform to the record of the case in the Patent Office.

Signed and sealed this 25th day of July, A. D. 1944.

Leslie Frazer

(Seal)

Acting Commissioner of Patents.
